CONSTANT FREQUENCY CIRCUITS

Application filed September 13, 1928, Serial No. 305,753. Renewed December 3, 1931.

This invention relates to constant frequency circuits and has reference more particularly to high frequency vacuum tube oscillators of the type employed for heterodyne wavemeters and other similar uses. Prior to this time the difficulty which has existed in the design of a heterodyne wavemeter, when the electron tube is used as a generator, is the change in frequency due to the variations of the filament temperature, plate voltage, etc. This difficulty is still greater for frequencies as high as 3000 kilocycles or more because the plate grid capacity of the tube becomes very important in the behavior of the oscillating tube. As it is practically impossible to construct tubes having identical constants, the heterodyne must be recalibrated every time the tube is changed. It is also well known that when using frequencies above 1000 kilocycles it is practically impossible to maintain the frequency of a vacuum tube oscillator within the limits required for a good reception of radio signals. Among the causes which produce the undesired shift in frequency I can enumerate the fluctuations in the plate voltage and filament temperature, the changes in tube characteristics, the swinging of the antenna, etc. If the oscillator is used as a heterodyne wavemeter the instrument must be calibrated not only when the tube is replaced but also several times during the normal life of the same tube. Moreover, great care should be taken in maintaining the filament temperature and the plate voltage as constant as possible. This is a very tedious and expensive process so that, in the modern practice, a Piezo electric crystal is preferred to control and maintain the frequency of vacuum tube oscillators. The crystal controlled vacuum tube oscillators are, however, expensive and lack in flexibility when the same oscillator is desired to cover a wide band of frequencies. Another object of this invention is to provide a vacuum tube oscillator able to maintain, to a high degree, constant frequency and having all the flexibility desired. Still another object of this invention is to devise a vacuum tube oscillator that is economical, efficient and easy to maintain and operate.

With these and other objects in view which may be incident to my improvements, the invention consists in the parts and combinations to be hereinafter set forth and claimed, with the understanding that the several necessary elements comprising my invention may be varied in construction, proportion and arrangement, without departing from the spirit and scope of the appended claims.

In order to make my invention more clearly understood, I have shown in the accompanying drawing means for carrying the same into practical effect, without limiting the improvements in their useful application to the particular constructions, which, for the purpose of explanation, have been made the subject of illustration.

In the drawing:

Fig. 1 is a diagram of the preferred form of my improved circuit showing the several elements involved.

Fig. 2 is a diagram showing the electrical equivalent of the circuit shown in Fig. 1.

Fig. 3 is a diagram of a modified form of my improved circuit wherein the grid is maintained at ground potential.

Fig. 4 is a vector analysis illustrating more clearly the theory of the present invention.

Referring by numerals to the drawing wherein the same elements are designated by like symbols, the numerals 1, 2 and 3 designate respectively the plate, grid and filament of a vacuum tube comprising between grid and plate a specially designed oscillating circuit. This circuit is composed of a few turns of heavy metallic conductor, 4, and a variable condenser, 5, of unusually large value. 6 and 7 are ordinary radio frequency choke coils producing across the oscillating circuit 4-5 a composite driving electromotive force. 8 is another radio frequency choke which maintains the filament at higher radio frequency voltage than the filament power supply, which ordinarily has great stray capacity to ground. 9 is a grid condenser and 10 is a grid resistance or leak; these elements provide a proper bias to the

grid of the tube, thus maintaining the plate current within safe limits.

11 and 12 are fixed condensers of very large value; they bypass the radio frequency current flowing in the plate circuit. It is possible, therefore, to maintain the plate and the plate power supply at ground potential with respect to the high frequency oscillations.

10 Fig. 2 shows the electrical equivalent of the circuit and Fig. 4 the vector diagram of the high frequency voltages and currents flowing in it, with their respective phases.

When the tube is in oscillating condition 15 a high frequency electromotive force E_g appears in the grid circuit which produces an electromotive force μ times greater in the plate circuit; μ being the voltage amplification constant of the tube. A current

$$I_b = \frac{\mu E_g}{R_o + Z_p}$$

is produced therefore in the circuit. After flowing through the internal plate impedance, R_o , of the tube, I_b , splits into two components I_p and I_g . The grid current I_g divides itself further into I_c and I_L . On account of the ohmic resistances R_p and R_g , always present in the coils L_p and L_g , the plate voltages E_p and E_g are slightly less than 180° out of phase; their geometric sum builds and maintains a high voltage E_o across the low loss oscillating circuit. The inductance, L , being extremely small and the capacity of 35 the condenser, C , extremely large, the oscillating currents maintained therein are very large and nearly all the oscillating energy is located in this circuit. I have demonstrated this by placing high frequency meters in different sections of the circuits and the ratio

$$\frac{I_o}{I_c}$$

or

$$\frac{I_o}{I_L}$$

45 is found to be around 1/100 in a well designed circuit.

50 I have demonstrated the novel and useful features of my circuit by extensive research as follows:

1. A loop transmitter working around 3000 KC has been designed in which the number of turns in the coil has been reduced to 55 only one loop of copper or aluminum tubing of large dimensions. The energy is thus radiated directly from the source without transfer into another circuit, which may introduce losses and complications in the behavior of the tube. The frequency of this transmitter remains so constant that a hand driven generator may be used to supply the power required for the filament and plate circuit. With all the fluctuations in plate voltage and filament current produced by such

device the note of the signal is pure, and reliable communication can be assured at distances varying with the power of the tube.

2. When greater power is needed the circuit may be used as master oscillator driving 60 amplifying tubes able to handle greater power. The constancy of frequency of a transmitter properly designed along these principles can compare favorably with similar devices in which the frequency is controlled by crystals and has the advantage of much greater flexibility in adjusting the frequency to any desired value.

75 3. As a heterodyne wavemeter the circuit has marked advantages over the crystal controlled circuits.

At 3000 kilocycles a similar device using 80 small tubes was able to maintain the frequency within 150 cycles when several tubes, picked at random, have been interchanged and the filament current or the plate voltage varied within 25% of their initial value.

85 As compared with the frequency of 3000 kilocycles the instrument is able to maintain the calibration within

$$\left(\frac{150}{3,000,000} \times 100 \right) = .005\%$$

90 which is remarkable for such a simple device. To attain the same precision with a crystal controlled oscillator the calibration should be made at constant temperature and thereafter the crystal maintained in a special chamber provided with thermostats in order to keep the temperature constant.

95 Many other variations are possible within the scope of this invention. For instance, it is possible to maintain the grid at ground potential; in this case the circuit should be modified as shown in Fig. 4 and two radio frequency chokes 8 are needed to keep the filament 3 at higher voltage than the power supply. The plate supply is maintained also at ground potential by locating it on the grid side as shown. The bypass condensers, 11 and 12, are located in the new positions indicated.

100 From the foregoing description it is apparent that I have provided a circuit in which the value of L_p and L_g can be kept high and still have a very high natural frequency. At the same time the value of C is great because the two coils L_p and L_g are shunted by L which has a small value of inductance. Therefore the frequency of my improved circuit is not far from the natural frequency of the circuit L, C .

105 The symbols and nomenclature employed in this specification are standard.

110 While I have shown and described the preferred embodiment of my invention, I wish it to be understood that I do not confine myself to the precise details of construction herein set forth, by way of illustration, as it is apparent that many changes and variations may

be made therein, by those skilled in the art, without departing from the spirit of the invention, or exceeding the scope of the appended claims.

5. I claim:

1. In a high frequency circuit, a vacuum tube having a filament grid and plate, a low loss oscillating circuit of small inductance and large capacitance connected across said grid and plate, and a plurality of radio frequency choke coils connected between the filament and the grid on one side and the filament and plate on the other producing across said oscillating circuit a driving electromotive force.

10. 2. A vacuum tube having a filament, grid and plate, a tank circuit comprising a low inductance, large capacitance and low losses connected across the grid and plate, a coil between the filament and grid and a second coil between the filament and plate of the tube.

15. 3. A vacuum tube having a filament, grid and plate a low loss tank circuit comprising a low inductance and large capacitance connected across the grid and plate, and means to produce high frequency oscillations in said tank circuit comprising two coils placed respectively between the filament and each of 20 the cold electrodes of the tube.

25. 4. A vacuum tube having a filament, grid and plate, a low loss tank circuit comprising a low inductance and large capacitance connected across the grid and plate and means to produce high frequency oscillation in the 30 tank circuit comprising two coils placed respectively between the filament and each of the cold electrodes of the tube.

35. 5. A vacuum tube having a filament, plate and grid, a low loss tank circuit comprising a low inductance and large capacitance connected across the grid and plate, and means to excite the tank circuit by high frequency voltage comprising two coils placed respectively and independently in the grid and plate circuits of the tube.

40. 6. A vacuum tube having a filament, grid and plate, a tank circuit comprising a low inductance and a large capacitance connected across the grid and plate, means to excite the tank circuit by high frequency voltage produced by the geometric sum of two electromotive forces comprising two coils placed respectively and independently in the grid and plate circuits of the tube.

45. 7. A vacuum tube oscillator including a filament, grid and plate, a tank circuit connected between the plate and grid of the tube, and means to induce high frequency oscillations in the tank circuit by two electromotive forces substantially 180° out of phase comprising two coils connecting respectively the filament and grid on one side and the filament and plate on the other side.

50. 8. A vacuum tube oscillator including a

filament, plate and grid, a low loss tank circuit connected between the grid and plate, and means to induce high frequency oscillations in the tank circuits comprising two coils placed respectively and independently in the grid and plate circuit of said tube so as to produce a composite driving electromotive force, and in which the high frequency oscillations are rendered independent of the interelectrode capacities of the tube.

55. 9. A vacuum tube oscillator comprising a filament, grid and plate, a tank circuit including a low inductance and large capacitance connected across the grid and the plate, means to produce high frequency oscillations in the tank circuit comprising two coils connected respectively between the grid and filament and between the plate and filament of the tube whereby the exciting independent electromotive forces generated in the grid and plate circuits maintain their frequency constant when the filament temperature varies within the limits of the order of 25% of the normal value.

60. 10. A vacuum tube oscillator comprising a filament, grid and plate, a tank circuit including a low inductance and large capacitance connected across the grid and plate, means to produce high frequency oscillations in the tank circuit comprising two coils respectively between the grid and plate of the tube whereby the exciting independent electromotive forces generated in the grid and plate circuits maintain their frequency constant when the steady plate voltage is varied within 50% of the normal value.

65. 11. A vacuum tube oscillator comprising a filament, grid and plate, a tank circuit connected across the grid and plate including a low inductance and high capacitance, a coil placed between the filament and grid and another coil placed between the filament and plate of the tube whereby high frequency oscillations are produced in the tank circuit and are rendered substantially independent of the length of the leads connecting the plate and grid to the tank circuit.

70. 12. A vacuum tube oscillator comprising a filament, grid and plate, a tank circuit connected across the grid and plate including a low inductance and high capacitance, a coil connected between the filament and grid and another coil connected between the filament and plate of the tube whereby high frequency oscillations are produced in the tank circuit and are rendered independent of the lengths of the leads connecting the filament and plate circuit to the low and high tension batteries.

75. 13. A constant frequency oscillator comprising a grid circuit, a plate circuit and a tank circuit having an inductance and a capacity connected between the grid and plate circuits, the characteristics of the tank circuit being such as to render the stray capacities 80

in the associated circuits substantially negligible.

14. A constant frequency oscillator comprising grid and plate circuits, a tank circuit having a small inductance and large capacity connected between the grid and plate circuits, the characteristics of the tank circuit being so chosen as to render stray capacities in the associated circuits substantially negligible.
15. In a high frequency circuit, a vacuum tube having filament, grid, and plate, a low loss oscillating circuit of small inductance and large capacitance connected across said grid and plate, and a plurality of radio frequency choke coils at least one of which is connected between the filament and the grid, producing across said oscillating circuit a driving electromotive force.
16. In a high frequency circuit, a vacuum tube having filament, grid, and plate, a low loss oscillating circuit of small inductance and large capacitance connected across said grid and plate, and a plurality of radio frequency choke coils, at least one of which is connected between the filament and the plate, producing across said oscillating circuit a driving electromotive force.
17. A constant frequency oscillator comprising a grid circuit, a plate circuit and a tank circuit having a fixed inductance and a variable capacity connected between the grid and plate circuits, the characteristics of the tank circuit being such as to render the stray capacities in the associated circuits substantially negligible.
18. A constant frequency oscillator comprising grid and plate circuits, a tank circuit having a small fixed inductance and large variable capacity connected between the grid and plate circuits, the characteristics of the tank circuit being so chosen as to render stray capacities in the associated circuits substantially negligible.

45. In testimony whereof I affix my signature.
CONSTANTIN D. BARBULESCO.
